CLAIM

The ornamental design for a cooking device, as shown and described.

DESCRIPTION

FIG. 1 is a perspective view of a cooking device showing our new design;

FIG. 2 is a left side elevational view thereof;

FIG. 3 is a front elevational view thereof;

FIG. 4 is a top plan view thereof;

FIG. 5 is a bottom plan view thereof.

FIG. 6 is a right side elevational view thereof; and,
FIG. 7 is a rear elevational view thereof.

The broken lines shown in FIG. 5 are for illustrative purposes only and form no part of the claimed design.
